UNITED STATES PATENT OFFICE.

MARK MARTIN KERR, OF CINCINNATI, OHIO.

COMPRESS.

SPECIFICATION forming part of Letters Patent No. 707,426, dated August 19, 1902.

Application filed April 10, 1902. Serial No. 102,303. (No model.)

To all whom it may concern:

Be it known that I, MARK MARTIN KERR, a citizen of the United States, residing at Cincinnati, in the county of Hamilton and State 5 of Ohio, have invented a new and useful Compress, of which the following is a specification.

My invention relates to certain improvements in devices employed for the treatment of varicocele, and has for its principal object 10 to provide an improved form of compress, by which any desired pressure may be maintained on the affected parts.

A further object of the invention is to provide of device of this character in which the 15 pressure may be adjusted to any desired extent and maintained as a constant pressure.

A still further object is to provide for the ready adjustment of the supporting-straps and to render the device readily removable 20 without disturbing the supporting-belt.

A still further object is to provide for the employment of a non-elastic apron and to simplify the construction and arrangement of parts, with a view of strengthening the apron 25 and its support.

With these and other objects in view the invention consists in the novel construction and arrangement of parts hereinafter described, illustrated in the accompanying 30 drawings, and particularly pointed out in the appended claim.

In the drawings, Figure 1 is a perspective view of a compress constructed in accordance with my invention. Fig. 2 is an elevation of 35 the compressing-apron and its supporting-straps, illustrating the method of connecting the straps to each other and to the apron. Fig. 3 is a detail view of the adjustable buckle carried by the waist-belt and serving to support the apron-straps.

Similar numerals of reference are employed to indicate corresponding parts throughout the several figures of the drawings.

The device is employed principally for the 45 treatment of varicocele and is designed to exert constant pressure on the affected parts, as distinguished from the usual supporters and similar devices which employ receiving-pouches of a more or less elastic character.

Referring to the drawings, 10 indicates a waist-belt having at one end a buckle 11 for the reception of the opposite end of the belt

to permit of proper adjustment. On the belt are arranged a pair of sliding buckles each comprising a metallic plate 12, provided with 55 a pair of slots 13, through which the belt is passed, the walls of the slots being bent at a slight angle in order to hold the buckle in any adjusted position. On the lower portion of the plate 12 is clamped a slotted plate 14, 60 forming two bars, over the upper of which passes a strap 15, that portion of the strap between the bar and the belt being confined in place by the friction between the two. Two straps are employed, each of precisely the 65 same construction and each carrying at one end a buckle 16, which is disposed in front of the body of the wearer, the straps thence passing down under the body and crossing each other, as indicated at 17. The straps 70 then pass up around the rear portion and sides of the body, over the bars 14, and thence down to a buckle 16 on the front end of the opposite strap.

20 designates a triangular piece of inelastic 75 webbing having at its edges a suitable binding or reinforcing tape 21, the side tapes being stitched to the supporting-straps 15 from the crossing-point 17 to a point just below the buckles 16 and forming a flat V-shaped apron 80 which may be adjusted in position under any desired strain by shortening the strap 15. The pressure may be regulated in a variety of ways and any desired adjustment be obtained by shifting the position of the belt-buckles, or by drawing the front end of the supporting-strap up through the slotted plate 14 and over the supporting-bar, or by an adjustment in the reverse direction, as may be required, and after the adjustment of the 90 straps to conform to the body the pressure may be regulated by drawing more or less of the strap ends through the buckles 16. The position of the buckle 16 also forms a convenient means of temporarily removing the 95 apron during the day and permits of proper loosening or tightening of the apron at any time without entirely removing the device from the person.

While the construction herein described, 100 and illustrated in the accompanying drawings, is the preferred form of the device, it is obvious that various changes in the form, proportions, size, and minor details of the

structure may be made without departing from the spirit or sacrificing any of the advantages of my invention.

Having thus described my invention, what I claim is—

In a device of the class specified, an apron formed of a triangular section of netting having reinforced edges, and a supporting device comprising a pair of straps crossing each other at the lower corner of the netting and secured to the opposite edges thereof, said straps having terminal fastening devices at points above the top of the apron, a support-

ing-belt, adjustable buckles carried by the belt, the straps from each side of the apron 15 at the front of the body extending continuously to the buckle of the belt at the opposite side of the body and thence to the fastening devices above the apron.

In testimony that I claim the foregoing as 20 my own I have hereto affixed my signature in the presence of two witnesses.

MARK MARTIN KERR.
